UNITED STATES PATENT OFFICE.

SAM WHEELHOUSE, OF HEBDEN BRIDGE, ENGLAND.

RAILWAY-CHAIR.

No. 895,819.

Specification of Letters Patent.

Patented Aug. 11, 1908.

Application filed November 4, 1907. Serial No. 400,649.

To all whom it may concern:

Be it known that I, SAM WHEELHOUSE, a subject of the King of Great Britain, residing at Hebden Bridge, in the county of York, 5 England, have invented an Improved Railway-Chair, of which the following is a specification.

The object of my invention is to construct an improved railway chair which will facilitate the laying and securing of the rails therein, dispense with the wood chucks or wedges and fish plates usually employed, and permit of lineal expansion and contraction of said rails.

15 By my construction of chair, the greater the weight put upon the rails when laid the more securely are they held.

According to my invention, I preferably construct my improved chairs of two fixed 20 jaws upon each side with a suitable space between each pair, within which hinges or pivots a loose jaw of peculiar form, whose inner face is shaped in conformity with the sides of the rail. The bottom of the rail, when in 25 position within the chair, rests or beds upon a projecting wing or heel of the loose jaws in such a manner as to cause the upper portion of the jaws to grip or bear against the sides of the rail. A bolt or cotter passing through 30 the fixed jaws and behind each loose jaw holds the latter in position against the sides of the rail, and prevents the rail being lifted out of the chair.

I attain these objects by the mechanism 35 illustrated in the accompanying drawings, in which—

Figure 1 is a sectional end view of my improved railway chair, showing position of loose jaws when about to insert a section of 40 rail. Fig. 2 is a side view of my improved railway chair showing the rail secured in position within the chair. Fig. 3 is an end view of Fig. 2. Fig. 4 is a plan of Fig. 3.

Similar letters refer to similar parts 45 throughout the several views.

When constructing my improved chair I prefer to form the same with two fixed jaws or guiding standards A, A, upon each side. Hinging or pivoting between each pair of 50 jaws A, A, upon bolts or studs B, is a loose jaw C of special form, whose inner face corresponds in shape with the sides of the rail D.

The loose jaws C are turned back upon their pivots B when requiring to insert the rail, but

are restricted in such movement by a stop or 55 projection F coming in contact with a rib G on the base plate H of chair.

Upon placing the rail D in my improved chair, it is lowered between the fixed jaws A, and coming into contact with a projecting 60 heel or wing J of each loose jaw C, see Fig. 1, automatically tilts the latter forward until they come in contact with the sides of the rail. The wings J being now brought into position, see Fig. 2, serve as a support or 65 bearing for the rail which is also shared by the loose jaws aforesaid, so that the more weight put upon the rail and by the rail upon the wings J, the greater the grip of the loose jaws upon the sides of said rail, and the 70 more rigid it becomes.

The loose jaws C are secured in position after the insertion of the rail by cotters, pins, or bolts K passing through the fixed jaws A, A, and behind the loose jaws C; in this 75 manner the rail is securely fixed within the chair.

To prevent undue lineal movement of the rails and allow for expansion or contraction of the same, I preferably form a stud L upon 80 one of the loose jaws, which, when the jaws engage with the rails, fits within a suitable recess M in the rail.

When dealing with rail joints, I preferably form the chairs with three fixed and two 85 loose jaws upon each side.

What I claim as my invention, and desire to secure by Letters Patent, is—

In a railroad chair, the combination, with 90 a base-plate provided with two standards on each side of its middle portion, of opposed clamping-jaws having their lower parts pivoted between the said standards and provided with heels for the rail to rest on and having also lugs at their upper parts for gripping the rail, said lugs being movable between and guided by the upper parts of the 95 said standards, and locking-pins slidable in holes in the upper parts of the said standards behind the said lugs.

100 In testimony whereof I have signed my name to this specification in the presence of two subscribing witnesses.

SAM WHEELHOUSE.
